UNITED STATES PATENT OFFICE.

CECIL M. CLARKE, OF CHICAGO, ILLINOIS.

SHEATHING MATERIAL.

1,277,861.

Specification of Letters Patent.

Patented Sept. 3, 1918.

Application filed January 18, 1918. Serial No. 212,408.

To all whom it may concern:

Be it known that I, CECIL M. CLARKE, a citizen of the United States, residing at Chicago, in the county of Cook and State of Illinois, have invented a new and useful Improvement in Sheathing Materials, of which the following is a specification.

My invention relates, more particularly, to sheathing material for covering the sides 10 and roofs of buildings and which is formed of a foundation of waterproofed felt or any other suitable, preferably flexible, material and which preferably, though not necessarily, is provided with a wear-resisting 15 coating of any desirable form and which is exposed to the elements in the use of the sheathing, this coating being preferably formed of any suitable particles attached to the foundation as is common in prepared 20 roofing.

More particularly stated, my invention relates to prepared sheathing material provided in strips, each of which presents a body portion from which a plurality of 25 shingle-forming sections, arranged in a series, project, these shingle-strips being so constructed that when assembled together in overlapping relation on a structure to be sheathed, the appearance will be the 30 same as that presented by a structure covered with shingles, as commonly laid. The present invention constitutes an improvement over the invention forming the subject of my pending application for United States 35 patent on sheathing material, Serial No. 209,008, filed Dec. 26, 1916, which is directed to the provision of shingle-strips of such construction that they will not present the disadvantage in use of becoming curled or 40 upwardly deflected at their unsecured corner-portions, by reason of the action of the sun, rain, and wind. My present invention provides for the accomplishment of the purpose just stated, and in addition, enhances 45 the shingle effect.

Referring to the accompanying drawing:

Figure 1 is a plan view of a shingle-strip constructed in accordance with my invention; and Fig. 2, a plan view of a section 50 of roofing formed of a plurality of the shingle-strips shown in Fig. 1.

My invention consists in providing a strip of any desirable sheathing material, as, for example, such as that above referred to, and 55 commonly employed for roofing purposes, of any desired length and width, with slots 3

provided therein, preferably in parallel relation and arranged crosswise of the strip at equal distances apart. These slots extend relatively close to one edge of the strip 60 which, in the construction illustrated, is the lower edge as represented, preferably to within about two inches of such edge, and preferably a relatively great distance from the opposite, upward, edge of the strip as 65 shown. Notches represented at 4 are provided in the lower edge of the strip, these notches, which are relatively shallow and in a strip of the size commonly provided may, for example, be approximately one inch 70 deep, alining with the slots 3. The slots 3 are thus connected across their opposite ends by portions of the sheathing strip as shown, and by the construction described, the lower edge of the sheathing strip presents a series of shingle-sections 5, which 75 are connected together at their lower ends by the uncut portions, or webs, 6 of the strip.

Each strip, which may be of such length as to provide any desired number of shingle-sections 5, is preferably of such width that in the assembling of the strips on a structure to be sheathed, as shown in the drawing, and in accordance with the common practice of laying shingle-strips, the solid 80 portions 7 of the shingle-strips will be overlaid by portions of two superposed shingle-strips and each shingle-strip will expose to view shingle-sections 5 of sufficient dimensions to present the desired shingle appearance 85 to the structure covered by the strips. The slots 3, by preference, are of such dimensions and are so disposed relative to the opposite edges of the strip as shown, that the desired overlap referred to and shingle 90 appearance are presented while maintaining the body portion 7 of the strip in substantially unslotted condition, this being done by so disposing the slots 3 that when the strips are assembled, the upper end walls 100 of the slots will be covered by the lower edges of the overlying shingle sections 5.

In producing my improved shingle-strip, I may provide the foundation material, treated as desired, and coated, if desired, 105 to form a weatherproof wear-resisting material all in accordance with common practice, and then, by any suitable device or mechanism, cut the material into shingle-strips of any desired length, though it will 110 be understood that my invention is not limited to the use of any particular material,

nor to the production of the article by any particular method of manufacture.

A shingle-strip constructed in accordance with my invention presents in the finished article ready to be applied to a structure to be sheathed, a series of shingle-sections, the lower ends of which are restrained against curling or outward deflection under subjection of the elements, by the webs 6, and thus the shingle-sections 5 will lie flat against the portions which they superpose; and the provision of the relatively shallow notches 4 serves to enhance the shingle effect, without subjecting the shingle-sections to objectionable curling or outward deflection.

The shingle-strips are preferably laid in the overlapping relation, and with the shingle-sections of adjacent strips disposed in staggered relation, as shown in Fig. 2, and which is the common practice in the laying of shingle-strips to produce the same appearance as that presented by a structure sheathed with shingles.

While I have illustrated and described a particular construction in which my invention is embodied, I do not wish to be understood as intending to limit it thereto, as the same may be variously modified and altered without departing from the spirit of my invention.

What I claim as new and desire to secure by Letters Patent is—

1. As an article of manufacture, sheathing material formed of a strip of waterproof material containing a series of slots which extend at their ends short of opposite edges of said strip and form shingle-sections along one edge thereof, said slots extending relatively close to said last-referred to edge, whereby said slots are connected across their opposite ends by web-portions of said strip, one of the edges of said strip containing a series of relatively shallow notches, all of the portions of said strip being of substantially the same thickness and extending in the same plane adapting a plurality of strips of the sheathing material to be laid in flatwise relation without fastening devices engaging the exposed portions of said strips.

2. As an article of manufacture, sheathing material formed of a strip of waterproof material containing a series of slots which extend at their ends short of opposite edges of said strip and form shingle sections along one edge thereof, said slots ex-

tending relatively close to said last-referred to edge and relatively far from the opposite edge, whereby one edge portion of the strip and from which said shingle sections project, is unslotted through a large area and the said slots are connected across their opposite ends by web-portions of said strip, one of the edges of said strip containing a series of relatively shallow notches, all of the portions of said strip being of substantially the same thickness and extending in the same plane adapting a plurality of strips of the sheathing material to be laid in flatwise relation without fastening devices engaging the exposed portions of said strips.

3. As an article of manufacture sheathing material formed of a strip of waterproof material containing a series of slots which extend at their ends short of opposite edges of said strip and form shingle sections along one edge thereof, said slots extending relatively close to said last-referred to edge and the upper edges of said slots being closer to the lower edge of said strip than to the upper edge thereof, whereby said slots are connected across their opposite ends by web portions of said strip, one of the edges of said strip containing a series of relatively shallow notches, all of the portions of said strip being of substantially the same thickness and extending in the same plane adapting a plurality of strips of the sheathing material to be laid in flatwise relation without fastening devices engaging the exposed portions of said strips.

4. The combination with a structure to be sheathed, of sheathing material on said structure in the form of a plurality of strips arranged in overlapping relation and each formed of waterproof material containing a series of slots which extend at their ends short of opposite edges of said strip and form shingle sections along one edge thereof, said slots extending relatively close to said last-referred to edge, whereby the slots of each strip are connected across their opposite ends by web-portions of the strip, one of the edges of said strips containing a series of relatively shallow notches, all of the portions of each strip being of substantially the same thickness and extending in the same plane adapting the strips to be laid in flatwise relation, said strips being arranged with their shingle-sections in break-joint relation and with their exposed portions free of fastening devices.

CECIL M. CLARKE.
